(57) **CLAIM**

The ornamental design for a grid pillar for storage system, as shown and described.

DESCRIPTION

Figure 1.1 is a top view of a first embodiment of a grid pillar for storage system;

Figure 1.2 is a partial, enlarged front perspective view thereof;

Figure 1.3 is a perspective view thereof;

Figure 1.4 is another perspective view thereof; and

Figure 1.5 is another top view thereof.

Figure 2.0 is a perspective view of a second embodiment of a grid pillar for storage system.

The broken lines illustrate environment of the grid pillar for storage system that form no part of the claimed design.

The grid pillar for storage system is shown with a symbolic break in its length. The appearance of any portion of the article between the break lines forms no part of the claimed design.
